UNITED STATES PATENT OFFICE.

JOSEPH BREZIN AND LOUIS BERZON, OF PHILADELPHIA, PENNSYLVANIA, ASSIGNEES
OF ONE-THIRD TO SAID JOSEPH BREZIN, ONE-THIRD TO SAID LOUIS BERZON, AND
ONE-THIRD TO WILLIAM KOSAKOFF, OF PHILADELPHIA, PENNSYLVANIA.

BAG-FRAME LOCK.

Application filed July 14, 1921. Serial No. 434,535.

To all whom it may concern:

Be it known that we, JOSEPH BREZIN and LOUIS BERZON, citizens of the United States, residing at Philadelphia, county of Philadelphia and State of Pennsylvania, have invented a new and useful Improvement in Bag-Frame Locks, of which the following is a full, clear, and exact description, reference being had to the accompanying drawings, 10 which form a part of this specification.

This invention relates to an improvement in locks, and more particularly to locks for traveling bags, and is designed to provide a simple and efficient lock which can readily be assembled and secured in position.

The object of our invention is to provide a lock in which substantially all of the parts are made of metal stampings provided with riveting projections formed integral therewith which are arranged to be riveted in openings in other members for securing the parts to each other.

Another object of our invention is to provide a bolt controlling plate which is so arranged with relation to the bolt that a single spring may be used to retain the bolt controlling plate and lock plate in position.

Another object of the invention is to provide a bolt which is guided by three walls of the lock casing, and which is also so arranged that it is held to one of its seats by the bolt controlling plate arranged to move when the bolt is shifted to prevent movement of the bolt other than its reciprocating movement from one position to the other.

The precise nature of our invention will be understood by reference to the accompanying drawings, which will now be described, it being premised, however, that changes may be made in the construction without departing from the spirit and scope of our invention as defined in the appended claims.

Fig. 1 is a plan view of one form of lock made in accordance with this invention with the top plate removed and a portion of the bag frame in section.

Fig. 2 is a side elevation of the lock shown in Fig. 1.

Fig. 3 is a perspective view of the bolt and the control plate for the bolt.

Figs. 4 and 5 are detail plan views of the bolt and locking plate with the bolt in the

unlocking and locking positions, respectively.

Fig. 6 is a longitudinal sectional view of the lock looking in the opposite direction from that shown in Fig. 2.

In these drawings, 10 and 11 designate portions of frame members of a bag. 12 are hasps secured to the member 10 which are arranged to be engaged by suitable members in the lock secured to the frame member 11 to retain the bag in its closed position.

The lock mechanism is mounted in a casing 13 formed of a back plate which is riveted to the frame member 11, a body member having end walls, a bottom and a front wall, and a top plate. The casing body member may be formed of sheet metal, which is first blanked and then bent to shape by suitable dies. The body member is provided with suitable nibs or projections, which are bent after the parts are assembled to secure the back plate and top plate in position to the body member.

Slidably mounted in the casing is a bolt 14 having a foot 15 which engages the bottom of the casing, while the locking portion of the bolt is in sliding contact with the front wall of the casing.

Slidably mounted in the casing for vertical movement is a locking plate 16 having an upwardly extending finger piece 17 which is movable in a guide 18 on the top plate. This finger piece is of the usual hollow form, and is provided with a key post 19 riveted to the lock plate. 20 are hasp projections on the rear edge of the lock plate for engaging the hasps 12 on the frame member 10 to hold the bag in its closed position. When the bag is in its closed position, the hasps 12 extend through suitable openings in the walls of the lock casing 13.

These projections are formed by pressing indents in the under side of the lock plate to form vertical hasp engaging edges at the back of the portions, and downwardly and forwardly sloping cam faces which merge into the top surface of the lock plate, and form cams for depressing the lock plate against the action of its retaining spring hereinafter described when the bag is closed.

By forming the hasp projections in the manner above described, easy and smoothly acting cams are formed by the stamping op-

eration as well as projections which are suitably unbendable.

Supported on the foot 15 and of a width and length to substantially fill the space between the end walls and front wall of the casing 13 and the inner face of the lock plate 14 is a bolt control plate 21.

22 are recesses formed in the bottom of the plate 21 which are stamped therein, and 23 is a projection on the upper face of the foot 15 of the bolt. 24 is a leaf spring adapted to retain the lock plate 16 and the bolt control plate 21 in their normal positions. The bolt 14 is provided with recesses or cut-away portions 25 which are directly under projections 26 on the lock plate 16 when the bolt is in its unlocked position, as shown in Figs. 4 and 6, so that the lock plate is free to be depressed against the action of the spring 24. When the bolt is in the position shown in Fig. 5, the projections on the bolt at the right side of the cut-away portions 25 (see Figs. 3, 4 and 5) are shifted under the projections 26 on the plate 16, as shown in Fig. 5, and lock the plate against movement. 27 is a key slot in the bolt 14 which is adapted to receive a key to shift the bolt from locking to unlocking or from unlocking to locking positions.

In Fig. 6 the bolt is shown in its unlocked position with the lock plate 16 depressed to free the hasps and in which the projection 23 on the bolt foot is in the left hand recess 22 in the bolt control plate 21. When it is desired to lock the bag, the hasps 12 are moved into engagement with the projections 20, the key is inserted and turned and the bolt shifted to the right (as viewed in Fig. 6) to shift the projections of the bolt 14 under the projections 26 on the lock plate, so that the lock plate is locked by the bolt while the hasps are locked by the projections 20 on the lock plate. When the bolt is in its locking position, the projection 23 on the foot of the bolt is shifted from the left hand notch 22 in the control plate 21 (as viewed in Fig. 6) and as the control plate is retained in engagement with the foot 14 of the bolt by the spring 24, the plate 21 will retain the bolt in either of its key shifted positions.

As the control plate is raised against the action of the spring 24, when the bolt is shifted from one position to the other, the bolt 14 is only subjected to a sliding movement in the casing and is always held against the bottom of the casing 13 by the action of spring 24.

The advantages of our invention result from the provision of a lock for bags in which the bolt is provided with a foot which is guided by the bottom wall and the two side walls of the casing. Further, from the provision of a bolt control plate on the foot

of the bolt together with spring means for retaining the lock plate and bolt control plate in positions.

Also from the provision of locking recesses and projections on the bolt foot and the control plate arranged to retain the bolt in its shifted position, and which are so arranged that the bolt can be shifted longitudinally without raising the bolt.

Another advantage results from the provision of a locking plate in which the hasp lugs are pressed in the body of the plate so that the cam faces thereof merge into one face of the lock plate and form smooth easy acting cams for depressing the locking plate.

Having now fully described our invention, what we claim and desire to protect by Letters Patent is:

1. A device of the character described comprising a casing, a lock plate mounted in the casing, a bolt slidably mounted in the casing arranged to be moved into and out of locking engagement with the lock plate, said bolt having a flange in engagement with the bottom of the casing, a bolt control plate in the casing on the bolt flange, interlocking projections and recesses on the flange and the bolt control plate, and a spring interposed between the control plate and the lock plate.

2. A device of the character described having a casing with a bottom and two side members, a bolt arranged to lie along one side member and having a foot member extending from one side member to the other resting on the bottom of the casing, a lock plate arranged to be locked by the bolt, and a spring interposed between the flange on the bolt and the lock plate.

3. A device of the character described having a casing with top, bottom and two side walls, a lock plate arranged to reciprocate in the casing, a bolt arranged to reciprocate in the casing at right angles to the movement of the lock plate, there being interlocking means between the bolt and locking plate to lock the plate against movement when the bolt is in one position and to permit the plate to be moved when the bolt is in another position, a flange on the bolt extending from side to side of the casing and in engagement with the bottom of the casing, the bottom and side walls forming guides for the bolt, a bolt control plate resting on the flange on the bolt, interlocking means on the flange on the bolt and the control plate, and a leaf spring interposed between the control plate and the lock plate.

In testimony of which invention we have hereunto set our hands, at Philadelphia, Pa., on this 11th day of July, 1921.

JOSEPH BREZIN.
LOUIS BERZON.
